METHOD OF MAKING HYPOSULFITES BY
MEANS OF AMALGAM

Souren Z. Avedikian, Larchmont, N. Y.

Application October 23, 1950, Serial No. 191,583

8 Claims. (Cl. 23—116)

1

This invention relates to the manufacture of hyposulfites, for example, to the production of sodium hyposulfite, $Na_2S_2O_4$, known commercially as sodium hydrosulfite. More particularly the invention relates to the manufacture by the direct reduction of the bisulfite in aqueous medium by means of the amalgam of the metallic element the hyposulfite of which it is desired to produce. Specifically, in the production of sodium hyposulfite, sodium bisulfite in aqueous medium is reduced by means of sodium amalgam to give the desired end product, namely, sodium hyposulfite.

The prior art abounds in methods for producing hyposulfites. The following may be cited as examples:

1. The reaction of sodium amalgam with sodium bisulfite and/or with sulfur dioxide to give sodium hyposulfite;

2. The reaction of metallic sodium with sulfur dioxide in organic medium;

3. The electrolysis of sodium bisulfite in which bisulfite ion is reduced to hyposulfite ion at the cathode;

4. The reduction of sodium bisulfite and/or sulfur dioxide by means of sodium or ammonium formate;

5. The reaction of sulfur dioxide on zinc suspended in water to give zinc hyposulfite and treatment thereof with sodium hydroxide or sodium carbonate to give precipitate of zinc hydroxide or zinc carbonate in a solution of sodium hyposulfite, separating the precipitate from the solution by filtration or otherwise, and treating the solution further to recover sodium hyposulfite.

Of all the methods cited above, only the fifth has been applied commercially. Despite claims made of high yields, none of the methods cited in the prior art have been found economically practicable except the fifth. It is understood that the second is now used to a limited degree, its extensive application being limited by the utilization that can be made of organic by-products.

The I. G. Farben at Leverkusen, Germany, used the mercury cell to produce sodium amalgam "to make sodium hydrosulfite when the price of zinc was high. At one time 30 to 50 tons of sodium hydrosulfite per month were made from sodium amalgam. The process was discontinued when the price of zinc dropped. . . . The overall yield was 52-53% on the current." This excerpt is from FIAT Final Report No. 818 dated June 25, 1946 entitled "Use of Sodium Amalgam for Reduction of Nitrobenzene and Other Organic Compounds and Production of Sodium Hydrosulfite,"

2

by William C. Gardiner of Technical Industrial Intelligence Branch, U. S. Department of Commerce. It explains the reason for non-application of the method to date despite claims of high yields in the literature of record of the prior art.

It is an object of this invention to provide an improved method for making hyposulfite in accordance with the principles of the first method described above. More specifically, it is an object 10 of this invention to make the first method commercially practical by increasing substantially the yield of hyposulfite obtained in proportion to the power required; power being a substantial element of cost.

15 More specifically, it is an object of this invention to make sodium hyposulfite and other alkali metal hyposulfites such as those of potassium and lithium, more expeditiously and cheaply than by known methods. In addition to the high 20 yield obtained, this invention has the further advantage of providing a practical process in which the hyposulfite is precipitated out during the course of reaction thus making possible continuous operation.

25 Other objects, features and advantages of the invention will appear or be pointed out as the specification proceeds.

The drawing is a diagrammatic view of one apparatus by which the process of this invention 30 can be carried out.

In order to produce sodium hyposulfite, in accordance with the process of this invention, I use sodium amalgam to reduce the bisulfite ion, $(HSO_3)^-$, in aqueous medium, to hyposulfite ion, $(S_2O_4)^-$.

35 It was a most unexpected result, but I found that if I use an amalgam containing a concentration of 0.04% sodium, by weight, namely, substantially that percentage of metallic sodium 40 alloyed with or dissolved in 99.96% metallic mercury by weight, the sodium in the amalgam functions almost exclusively in reducing bisulfite to hyposulfite, in accordance with the following equation:

50 All references to percentages in the description that follows and the claims are by weight.

At a sodium concentration substantially greater than 0.04%, the sodium is spent in what I call the "water reaction" to produce sodium hydroxide 55 and gaseous hydrogen with a resultant lowered

yield of the desired end product. This water reaction is illustrated by the equation

With my invention and with metallic sodium concentrations of 0.04% and lower, hyposulfite yields of over 90%, based on the quantity of sodium consumed, are obtained, but as the concentration is increased, the yields become progressively lower, for example, as low as yields of the order of 25% or less. The concentration of sodium in the amalgam should always be lower than approximately 0.1%.

I have also discovered that the time of contact between sodium amalgam and the hyposulfite solution should be kept at a minimum to reduce or prevent side reactions. I have found that under substantially identical conditions, except for the presence or absence of amalgam, decomposition of hyposulfite originally present in a system is of the order of 20% to 40% or more when the hyposulfite is in contact with amalgam whereas in the absence of amalgam decomposition is of a much lower magnitude. Furthermore, amalgam favors the conversion of hyposulfite to sulfide and thiosulfate. In my tower system described below the time of contact between amalgam and hyposulfite solution is reduced to a minimum and the surface area of continuous contact between the amalgam and the solution is small. The resulting decomposition is of the order of about 8% maximum.

I prefer to carry out the reaction between the sodium amalgam and sodium bisulfite in a tower column or tower 10 having a branch conduit 11 through which bisulfite solution, with which the tower is charged initially, is withdrawn. This solution passes through a cooler 13 to a pump 14 which discharges the solution through a filter or centrifuge 15 to a pH flow cell 17 from which the solution passes through a pipe 19 back to the tower 10. Refrigerating medium for the cooler 13 is supplied through pipe 20. The pipe 19 has one branch 21 which discharges solution into a branch 22 of the tower, and the other end of the pipe 19 leads downward to a discharge outlet 23 near the bottom of the tower. The solution is thus introduced to the tower both above and below the outlet 11.

There is a by-pass 26 around the filter 15 and there are valves on both sides of the filter 15 and in the by-pass line 26 for selectively controlling the flow of liquid through the filter or by-pass. The purpose of this by-pass is to permit opening of the filter and removal of crystals which have accumulated in it without stopping the circulation of liquid through the system.

Amalgam is supplied from a reservoir 28 through piping 30 to an inverted outlet 31 from which drops of the amalgam fall into the solution in the tower 10. The piping 30 includes a shut off valve 33 and drain valves 34. A gauge 36 extends upward from the piping 30 upstream from the valve 33 and there is a vent 37 downstream from this valve.

The tower 10 may be packed in order to afford a more intimate contact between the sodium amalgam and the sodium bisulfite in solution. It is not essential that the tower be packed, however, since small drops of amalgam have sufficient contact with the liquid when the tower is of substantial height. I prefer to use in the tower a concentration of bisulfite equivalent to 0.5 to 1.0 molar.

The spent amalgam, that is, amalgam which

has a substantially lower sodium concentration than the amalgam initially supplied to the tower, drops into a U-tube 40. This spent amalgam 42 eventually fills the U-tube which serves as a trap, and discharges into a spent amalgam reservoir 44 from which the mercury is taken to make new amalgam.

It is necessary to furnish an acidic substance to the system in order to regenerate the bisulfite or 10 to neutralize the sodium hydroxide formed (see Equation 1 above). Any suitable acid, for example, acetic acid which would not bring about a sharp drop in pH, that is, a sharp increase in hydrogen ion concentration or hydrogen ion activity, can be used. Sulfur dioxide gas, especially when supplied by surface absorption, is particularly suitable under the conditions of operation maintained in the tower system.

The sulfur dioxide gas is supplied from a controlled source to a pipe 48. This pipe leads into the space in the tower 10 above the level of the liquid. I prefer to operate the system with the sulfur dioxide under a slight pressure in order to facilitate dissolving of this gas in the liquid by 25 surface absorption. The higher the pressure, the greater the amount that will dissolve. This procedure makes possible convenient control of pH at approximately 5 to 6 or at a maximum of 7.

The solution in the tower becomes progressively richer in sodium hyposulfite. The various reactions taking place in the system may be represented by the following equations:

Summation of Equations 1 and 3 gives Equation 4.

The regeneration of bisulfite takes place in accordance with Equation 5, below.

The sulfur dioxide may also be shown as neutralizing the sodium hydroxide formed (see Equation 6, below).

I prefer to maintain the system at a temperature of 10° C. or lower. Under these conditions sodium hyposulfite precipitates out of solution in practically pure form, in well formed crystals that include water of crystallization. I maintain an inert atmosphere throughout the operation except for the sulfur dioxide above the liquid contents of the tower. The crystallization of sodium hyposulfite under these conditions of operation is also a most unexpected result since it occurs at a concentration of only about 6% which is the saturation concentration. According to data published in the prior art, solubility of sodium hyposulfite is represented at 1° C. to be about 16.5%, at 10° C. about 17.2%, and at 20° C. about 18.2%. Under the conditions of operation in my apparatus, the saturated solution from which sodium hyposulfite crystallizes out has a hyposulfite concentration of only about 6%.

These crystals are removed from the system at some region of the circulating circuit, and in the apparatus shown, the crystals are removed in the filter or centrifuge 15 located beyond the pump. This filter or centrifuge could be located ahead of the pump, but is preferably on the downstream side of the cooler 13 because the reduction

in temperature causes an increase in the precipitation. I treat the crystals to produce either sodium hydrosulfite of commerce, that is anhydrous sodium hyposulfite, or the formaldehyde complex, that is sodium formaldehyde sulfoxylate.

Instead of or complementary with well known methods of sodium hyposulfite recovery, I have also devised the following method to remove the water of crystallization. I let the crystals fall through a tower filled with alcohol or other suitable and effective dehydrating medium. I maintain the tower at about 52° C., and preferably between 60 and 70° C. The crystals of sodium hyposulfite which I collect from the tower are dried in a vacuum oven. The resulting product is the product of commerce known as sodium hydrosulfite. Sodium formaldehyde sulfoxylate is prepared by reacting the crystals from the amalgam reacting tower system with formaldehyde under suitable conditions.

For purging the tower of air and obtaining inert atmosphere at the beginning of an operation, the tower 10 is equipped with a pipe 52 through which carbon dioxide is introduced into the tower under the control of a shut-off valve 53. This carbon dioxide pipe extends downward through the tower and has a discharge outlet 55 at a low level in the tower. The inert atmosphere supplied to the tower at this low level forces the air out of the tower through a vent 56 which is thereafter closed before the sulfur dioxide supply is introduced into the tower by opening a valve 58.

At the lower end of the tower there is a sampling tube 60 communicating with the tube in which the spent amalgam accumulates. This sampling tube 60 is commanded by a valve 62 which can be opened whenever it become necessary to take a sample of the amalgam for a test. Another sampling line 64 with a valve 65 can be opened to take samples of the liquid for test purposes.

From a review of the description of my invention it will be apparent that the process involves three reactions. The first is the reduction reaction which is the productive reaction of the process. This is represented by Equation 1, above, in which the sodium amalgam reacts with the sodium bisulfite in aqueous solution to produce the sodium hyposulfite and the by-products of sodium hydroxide and water. The second is the neutralization of the sodium bisulfite to give sodium sulfite and water. This is represented by Equation 3. The third is the regeneration reaction in which bisulfite is regenerated by furnishing an acidic substance to the system, for example, sulfur dioxide. This is represented by Equation 5. The second and third reactions may be summarized and the result represented by Equation 6. In the system as operated, it is probable that none of the reactions occur to the exclusion of any of the others and that all take place at some period of the process depending upon the pH at that time. Repetition of the cycle represented by these equations brings about enrichment of the tower solution in respect to sodium hyposulfite finally resulting in its precipitation when its saturation concentration is reached.

With this invention, in which the concentration of the sodium in the amalgam is kept at a very low value, there is very little water reaction, represented by Equation 2 above. The reason for this is not clearly understood. If the concentration is too small, however, the amount of sodium hyposulfite that can be produced within a given time in any particular apparatus is unnecessarily

restricted. The concentration of sodium in the amalgam can be as high as 0.04% without causing substantial loss of sodium by the water reaction. The percentage concentration can be increased 5 slightly without producing a substantial waste of sodium, but as the concentration reaches approximately 0.10% of sodium, the waste of sodium becomes large.

The process of the invention has been described 10 in detail for sodium hyposulfite. Potassium hydrosulfite, lithium hydrosulfite, or any alkali metal hyposulfite can be produced by the method of this invention by merely substituting the bisulfite of the desired alkali metal for sodium bisulfite and 15 the amalgam of the desired alkali metal for sodium amalgam. For example, to produce potassium hydrosulfite, I use potassium bisulfite and potassium amalgam. The apparatus and method are otherwise the same.

20 The subject matter of this application is related to that of applicant's copending application, Serial No. 211656, filed February 19, 1951.

Various changes and modifications can be made 25 and features of the invention can be used alone or in different combinations without departing from the invention as defined in the claims.

I claim as my invention:

1. The method of making an alkali metal hydrosulfite which comprises introducing into a body of 30 aqueous solution of said alkali metal bisulfite successive particles of an amalgam of the alkali metal, passing the particles through the body of solution to a collection region, introducing the amalgam into said body of solution with a concentration of less than 0.1% of alkali metal in the amalgam, withdrawing the amalgam at lower alkali metal concentration from the collection region, and withdrawing alkali metal hydrosulfite from the body of solution at another region.

40 2. The method of making an alkali metal hydrosulfite, as described in claim 1, with the amalgam that is introduced into the body of solution having a concentration of the order of 0.04% of sodium and substantially less than 0.1%.

45 3. The method of making sodium hydrosulfite which comprises introducing successive particles of sodium amalgam into a body of aqueous solution of sodium bisulfite, passing the particles through the body of sodium bisulfite solution to a collection region, introducing the sodium amalgam into the body of solution with a concentration of less than 0.1% of sodium in the amalgam, withdrawing the amalgam at lower sodium concentration from the collection region, and withdrawing sodium hydrosulfite from the body of solution at another region.

50 4. The method of making sodium hydrosulfite, as described in claim 3 with the body of solution extending downwardly from a top at which the sodium amalgam is introduced into the column so that the sodium amalgam drops by gravity through the body of solution, and in which the collection region is at the bottom of the body of solution, circulating the bisulfite solution through 55 a by-pass from one region of said body of solution to another, and removing sodium hydrosulfite from the bisulfite solution during the passage of the solution through the by-pass.

60 5. The method of making sodium hydrosulfite, as described in claim 3, with the sodium amalgam introduced into the body of solution adjacent to the top of said body so that the sodium amalgam drops by gravity to the collection region, and in which the sodium amalgam has a concentration of the order of 0.04% of sodium and substan-

tially less than 0.1% at the region where the sodium amalgam is introduced into the bisulfite solution.

6. The method of making sodium hyposulfite, as described in claim 3, and in which sulphur dioxide is dissolved in the aqueous solution to convert sodium sulfite which forms as a by-product of the reaction in the body of solution back into sodium bisulfite which reacts with the sodium amalgam to produce additional sodium hyposulfite.

7. The method of making sodium hyposulfite, as described in claim 3, and in which the sodium amalgam introduced into the body of solution has a concentration of the order of 0.04% sodium in the amalgam and substantially less than 0.1%, and in which the surface of the reaction material is subjected to an atmosphere of sulphur dioxide which dissolves in the solution to convert the sodium sulfite by-product of the reaction back to sodium bisulfite which in turn reacts with the sodium in the amalgam to produce additional sodium hyposulfite.

8. The method of making sodium hyposulfite, as described in claim 3, with the concentration of

the sodium bisulfite equivalent to 0.5 to 1.0 molar, and the sodium amalgam introduced into the body of solution with a concentration of the order of 0.04% sodium in the amalgam and substantially less than 0.1%, subjecting the surface of the reacting materials to an atmosphere of sulphur dioxide under super atmospheric pressure that causes a substantial quantity of the sulphur dioxide to be dissolved in the body of solution to convert the sodium sulfite back into additional sodium bisulfite for reacting further with sodium of the amalgam, maintaining the body of solution at a temperature at least as low as 10° C. and maintaining the pH of the mixture at approximately 5 to 6.
